UNITED STATES PATENT OFFICE.

LEWIS J. CLAPP, OF CLAREMONT, NEW HAMPSHIRE, ASSIGNOR TO SULLIVAN MACHINERY COMPANY, A CORPORATION OF MASSACHUSETTS.

COMPRESSOR.

Application filed February 15, 1924. Serial No. 693,106.

To all whom it may concern:

Be it known that I, LEWIS J. CLAPP, a citizen of the United States, residing at Claremont, in the county of Sullivan and State of New Hampshire, have invented certain new and useful Improvements in Compressors, of which the following is a full, clear, and exact specification.

My invention relates to compressors, and particularly to compressors of the rotary type.

An object of my invention is to provide an improved compressor. Another object of my invention is to provide an improved compressor of the rotary type. A further object of my invention is to provide an improved compressor of the rotary type capable of compressing a fluid to a substantial pressure and yet so constructed and operating as to be as little wasteful of work during the bringing up of the pressure in the discharge line to the desired pressure as is practicable. A still further object is to provide a rotary compressor especially adapted to efficiently provide compressed fluid at different pressures. Other objects and advantages of my invention will hereinafter more fully appear.

In the accompanying drawings I have shown for purposes of illustration one form which my invention may assume in practice.

In these drawings.—

Fig. 1 is a central vertical transverse section through a compressor constructed in accordance with the illustrative embodiment of my invention.

Fig. 2 is a longitudinal vertical section on a plane corresponding to the line 2—2 of Fig. 1.

Fig. 3 is a detail in perspective.

In the form of my invention which I have selected for purposes of illustration the same is shown incorporated in a mechanism comprising a casing generally designated 1 and comprising a central section 2 and head sections 3 and 4. The central section is provided with intersecting cylindrical bores 5 and 6 in which there are rotatable rotors 7 and 8 which are journaled in any suitable manner, not shown, it being simply requisite that suitable bearings be provided and that one of the rotors be provided with an extended driving shaft 9 which may be driven to effect rotation of the rotors. Each of the rotors herein comprises a pair of end

sections having oppositely extending spiral tooth blades, these sections being designated 11 and 12 and the tooth blades illustrated at 13. Between each pair of sections 11 and 12 there is herein provided a spur gear section 14 whose teeth match with the ends of the tooth blades 13. It will be evident that when a pair of such rotors are arranged in juxtaposition to each other in the casing and with their tooth blades running close to the inner peripheries of the rotor chambers 5 and 6, there will be formed, depending upon the direction of rotation of the rotors, expansion or compression pockets, and further that air admitted to the spaces between the teeth will be, provided the direction of rotation is properly selected, entrapped and compressed and this air may be discharged at any time before the pockets vanish at the line of mesh of the rotors, dependent upon the nature of the discharge means provided. For the purpose of advantageously supplying fluid to the rotors the rotor chambers are caused to communicate with each other substantially throughout their lengths by cutting away a portion of the casing, producing a space as indicated at 15, to which space fluid may be supplied through either or both of the oppositely extending pipes 16 and 17.

Now briefly considering the mode of operation of a device of this sort, it will be apparent that whether or not there are spaced at the ends of the rotors, i. e., whether or not the rotors at their ends run in close relation to the heads, there will begin to be a compression of the fluid in the tooth pockets when, but only when, the outer extremities of the tooth blades on one rotor begin to roll into a tooth pocket on the other rotor. Accordingly, if no vent provided for this entrapped fluid until the fluid had been compressed to a pressure equal to the desired final discharge pressure of the compressor, there would be a considerable loss of work during the starting up of the system were the compressor to discharge to an empty receiver, as the fluid compressed would simply expand down to substantially the pressure in the receiver so that there would be quite a waste of power during the starting of the compressor. Moreover, were it desired to reduce the pressure maintained in the receiver to less than the final discharge pressure of the compressor with a discharge

designed for the higher pressure, there would be a constant waste of work throughout the entire operation of the compressor. I have accordingly provided means which will result in a more economical starting of the compressor and will, which is perhaps even more important, permit this compressor to operate with various discharge pressures and do so efficiently.

10 Means of the sort just referred to may assume various forms, but herein for purposes of illustration I have shown a construction in which the portion of the casing nearest the mesh line of the rotors at the discharge side of the casing is cut away for an extended distance adjacent the center of the rotors and in suitable guideways 21 there are slideable towards and from each other a pair of members 22 and 23 of such construction 15 that they exactly correspond in cross section to the material which has been removed. In other words, they are adapted to fit snugly down adjacent the teeth of the rotors. These members 22 and 23 are provided with 20 portions 24 and 25 respectively which extend into cylinder bores 26 and 27 within which bores pistons 28 and 29 are slideable, these pistons being secured to the portions 24 and 25. To the remote ends of the cylinders 25 20 fluid is admitted from the discharge chamber 30 of the compressor, this fluid passing through ports 31 and 32. It will be observed that a spring 33 of suitable strength is arranged in bores in the portions 24 and 25 and normally forces the members 22 and 23 apart. At this point it is desired to make it clear that it is not necessary to follow the precise construction shown for the members 22 and 23 may each obviously be made of 30 a length equal to one-half the full length of the rotors and they may be slideable through the heads 3 and 4, if desired there being pockets to receive such portions of these members as may project through the 35 heads at any time. With such a construction, instead of arranging the pistons 28 and 29 and their corresponding cylinders as illustrated, these would be raised above the sliding members and would be connected 40 thereto by stems leading to suitable bosses projecting from the upper surfaces of the slides. This would do away with the existence of the pockets 35 and 36 shown, which pockets are necessary herein to permit the requisite movement of the parts 22 and 23, but which in normal operation exert no substantial influence on the operation of the compressor. It will be understood that the greatest perfection of result would however 45 probably come from the use of the longer slides described.

It will be understood that the strength of the spring 33 will be proportioned to the areas of the adjacent faces of the members 50 22 and 23, to the areas of the remote faces

of these members, and to the areas of the pistons 28 and 29, these parts being so proportioned as to cause the members 22 and 23 to be forced apart to their maximum possible distance from each other during 70 the period when there is no pressure in the compressor discharge line and to approach each other progressively as the discharge line pressure builds up until at the maximum discharge pressure desired for the compressor, the members 22 and 23 will be spaced apart such a distance that at the moment of communication with the space between the members, the pressure within the tooth pockets will be substantially equal 75 to or only slightly above the pressure in the space 30. It will be evident from what has been said that if the compressor is starting up and there is no pressure in the chamber 30 above atmospheric, the members 22 and 23 will be spaced apart the maximum distance permitted and so but little compression within the tooth pockets will take place before the entrapped fluid will be brought into communication with the spaces 80 between the adjacent ends of the members 22 and 23. Accordingly, the free expansion of the fluid into the chamber 30 and the discharge line will be reduced to a minimum. As the pressure in the discharge line gradually builds up, the pressure passing through the ports 31 and 32 will act on the pistons 28 and 29 and will cause the members 22 and 23 to approach each other and so the discharge orifice, so to speak, will always bear such relation to the pockets containing the fluid under compression that these pockets will be brought into communication with the discharge orifice substantially immediately after the instant when 90 the pressure in the pocket becomes equal to the pressure in the discharge line. This will of course be a much more economical arrangement than would be produced with an orifice of constant cross sectional area and it permits, moreover, a compressor which is capable of producing and maintaining a pressure of one hundred pounds, for example, to operate satisfactorily and without waste of power with a discharge pressure of say fifty pounds, all that is necessary being that the demand for air at fifty pounds pressure be increased or the speed of the compressor be so cut down that 100 so much air will not be discharged into the discharge line as to raise the pressure. The utility and value of this feature will be readily appreciated by any one skilled in this art.

While I have in this application specifically described one form which my invention may assume in practice, it will be understood that this form of the same is shown for purposes of illustration and that the invention may be modified and embodied in 115 120 125 130

various other forms without departing from its spirit or the scope of the appended claims.

What I claim as new and desire to secure by Letters Patent is:

1. In combination, in a compressor, a casting having intercommunicating rotor chambers, rotors therein having intermeshing spiral tooth blades forming longitudinally contracting compression pockets, and discharge means comprising a port communicable with said compression pockets for different portions of their existence. 70
2. In combination, in a compressor, a casting having intercommunicating rotor chambers, rotors therein having intermeshing spiral tooth blades forming longitudinally contracting compression pockets, and discharge means of gradually variable area operative to permit discharge of fluid from said pockets as soon as the pressure therein exceeds the pressure in the discharge line by a certain small amount. 75
3. In combination, in a compressor, a casting having intercommunicating rotor chambers, rotors therein having intermeshing tooth blades forming compression pockets, and discharge means having a movable bounding wall and operative to permit discharge of fluid from said pockets as soon as the pressure therein exceeds the pressure in the discharge line by a certain small amount. 80
4. In combination, in a compressor, a casting having intercommunicating rotor chambers, rotors therein having intermeshing spiral tooth blades forming compression pockets, and discharge means having a plurality of movable bounding walls and operative to permit discharge of fluid from said pockets as soon as the pressure therein exceeds the pressure in the discharge line by a certain small amount. 85
5. In combination, in a compressor, a casting having intercommunicating rotor chambers, rotors therein having intermeshing spiral tooth blades forming compression pockets, and discharge means having a movable bounding wall whose position is controlled by compressor discharge pressure and operative to permit discharge of fluid from said pockets as soon as the pressure therein exceeds the pressure in the discharge line by a certain small amount. 90
6. In combination, in a compressor, a casting having intercommunicating rotor chambers, rotors therein having intermeshing spiral tooth blades forming compression pockets, and discharge means having a plurality of movable bounding walls whose positions are controlled by discharge pressure and operative to permit discharge of fluid from said pockets as soon as the pressure therein exceeds the pressure in the discharge line by a certain small amount. 95
7. In combination, in a compressor, a cas- 100
- ing having intercommunicating rotor chambers, rotors therein having intermeshing spiral tooth blades forming compression pock- 105
- ets, and discharge means having a bounding wall movable to diminish the area of the discharge orifice as compressor discharge pressure increases and operative to permit discharge of fluid from said pockets as soon as the pressure therein exceeds the pressure in the discharge line by a certain small amount. 110
8. In combination, in a compressor, a casting having intercommunicating rotor chambers, rotors therein having intermeshing spiral tooth blades forming compression pock- 115
- ets, and discharge means having a plurality of movable walls normally spaced apart and movable in accordance with compressor discharge pressure to reduce the effective area of the compressor discharge means and operative to permit discharge of fluid from said pockets as soon as the pressure therein exceeds the pressure in the discharge line by a certain small amount. 120
9. In a rotary compressor, the combination with a pair of rotors each provided with a plurality of teeth cooperating to form between successive teeth pockets decreasing in size upon rotation of the rotors, of means forming a discharge port adapted to communicate directly with the pockets at their moment of vanishing and including means for varying the duration of the period of communication of each pocket with said discharge port. 125
10. In a rotary compressor, the combination with a pair of toothed rotors cooperat- 130
- ing to form between their teeth pockets diminishing in size upon rotation of the rotors, of a fluid discharge port communicating directly with the compression pockets and having a bounding edge adjustable in a direction perpendicular to the plane of the pitch circle of the rotor teeth. 135
11. In a rotary compressor, the combination with a pair of toothed rotors co- 140
- operating to form between their teeth pockets decreasing in size upon rotation of the rotors, of a fluid discharge port having a bounding edge into communication with which said pockets move during compression and provided with a bounding edge adjustable to vary the time of communica- 145
- tion. 150
12. In a rotary compressor, the combi- 155
- nation with a pair of toothed rotors co- 160
- operating to form between their teeth pockets decreasing in size upon rotation of the rotors, of a fluid discharge port having a bounding edge into communication with which said pockets move during compression and provided with a bounding edge adjust- 165
- able to vary the duration of the period of communication of each pocket with the compressor discharge. 170
13. In a rotary compressor, the combina- 175

tion with a casing having a pair of toothed rotors cooperating to form between successive teeth pockets diminishing in size upon rotation of the rotors, of a discharge port opening into the interior of said casing at a point to communicate with said vanishing pockets immediately prior to their vanishing, and means whereby one dimension of said port may be varied to change the period of the latter's communication with each of said pockets.

14. In combination, a casing having overlapping bores, a pair of rotors disposed therein and having intermeshing teeth, and a member movable over the surface thereof.

15. In combination, a casing having overlapping bores, a pair of rotors disposed therein and having intermeshing teeth, and a member longitudinally movable over the surface thereof.

16. In combination, a casing having overlapping bores, a pair of rotors disposed therein and having intermeshing teeth, and a member disposed adjacent the mesh line of said rotors and movable longitudinally thereof.

17. In a rotary compressor, the combination with a casing having a pair of intermeshing toothed compressor rotors, and means disposed and movable along a rotor

periphery for controlling the pressure of the fluid compressed.

18. In a rotary compressor, the combination with a casing having a pair of intermeshing toothed rotors, a pressure fluid discharge passage, means disposed and movable along the periphery of said rotors for controlling the pressure of the fluid compressed, and means whereby said control is effected automatically in accordance with the pressure in the discharge passage.

19. In a rotary compressor, the combination with a casing having intermeshing spiral toothed rotors adapted to form longitudinally contracting compression pockets, of a discharge port, and means operative after said pockets are filled for controlling the pressure of the fluid compressed in said pockets.

20. In a rotary compressor, the combination with a casing having a pair of cooperating rotors mounted on axes always relatively fixed, inlet and discharge passages communicating therewith, and means operative independently of the inlet passage for controlling the degree of pressure to which fluid is compressed.

In testimony whereof I affix my signature.

LEWIS J. CLAPP.
